UNITED STATES PATENT OFFICE.

GEORGE M. DE VILBISS, OF STELLA, NEBRASKA.

BOX-CAR DOOR.

Application filed June 24, 1919. Serial No. 306,347.

To all whom it may concern:

Be it known that I, GEORGE M. DE VILBISS, a citizen of the United States, residing at Stella, in the county of Richardson 5 and State of Nebraska, have invented certain new and useful Improvements in Box-Car Doors; and I do hereby declare the following to be a full, clear, and exact description of the invention, such as will enable others skilled in the art to which it appertains to make and use the same.

This invention relates to new and useful improvements in grain car doors and has for one of its objects the provision of a device of this character which will readily permit the filling and emptying of a box car of grain and also permit of the car being loaded to its fullest capacity with freight other than grain without lifting the 20 freight over the entire height of the door.

Another object of this invention is the provision of a box car door of the above stated character, which shall be simple, durable and efficient, and which may be manufactured and sold at a comparatively low cost.

With these and other objects in view as will become more apparent as the description proceeds, the invention consists in certain 30 novel features of construction, combination, and arrangement of parts as will be hereinafter more fully described and claimed.

For a complete understanding of my invention, reference is to be had to the following description and accompanying drawings, in which:

Figure 1 is a rear elevation partly in section of a box car door constructed in accordance with my invention,

Figure 2 is a front elevation of the same,

Fig. 3 is a sectional view taken on line 3—3 of Figure 1,

Fig. 4 is a sectional view taken on line 45 4—4 of Figure 1, illustrating the sections of the sectional door overlapping each other,

Referring in detail to the drawings the numeral 1 indicates the side of a box car having a doorway 2 extending from its upper edge to its lower edge and which doorway has positioned at its side edges vertically disposed supporting posts 3. A solid door 4 is hinged to one of the posts 3 as illustrated at 5 and said door extends from the lower end of the doorway to a point adja-

cent the upper end of the doorway so as to form a filling space. The door 4 is adapted to close a portion of the doorway while a plurality of doors 6 are adapted to close the other portions of the doorway. The doors 6 are each hinged to the other post 3 as illustrated at 7 and are arranged one above the other as clearly shown in the drawings. The doors 4 and 6 are arranged to swing inwardly against the inner face of the side of the car when not in use. The doors 6 are provided with flanges 8 that are adapted to overlap or engage the adjacent door so as to prevent the grain in the car from leaking between the doors 6. The doors 6 at their free ends are also provided with flanges 9 that engage the free edge of the door 4 to limit the outward movement of said door 4 and prevent accidental inward movement of said doors 6. The lower portion of the door 4 is provided with an opening 10 that is closed by a hinged door 11. The door 11 is so hinged to the door 4 that the same swings outwardly of the car for the purpose of permitting the grain within the car to drain therefrom when desired. The door 11 is held in closed position by means of spring catches 12.

The door 4 upon its outer face has pivoted thereto a locking lever 13 to which are pivoted upwardly and downwardly extending locking bars 14 that are slidable through brackets 15 secured to the door 4. The ends of the locking bars 14 are adapted to be received within socketed members 16 secured to the top and bottom of the car for the purpose of locking or holding the door 4 against outward movement of the car when in door closing position.

From the foregoing description it will be noted that the door 4 can be locked in door closing position against inward and outward movement, and when so locked the doors 6 will be held against swinging inwardly of the car by the flanges thereof engaging the door 4.

When it is desired to load the car with freight other than that of grain, the door 4 is locked in a closed position and the freight is loaded in to the car through the remaining portion of the doorway which is left open when the doors 6 are in open position, and as the car becomes filled with freight the doors 6 can be moved to closed position one after another, each time first swinging door 4 slightly inwardly so as to

be out of the path of movement of flanges 9 thus obviating the necessity of lifting the freight over the doors when desiring to load the car to its fullest capacity.

5 While I have shown and described the preferred embodiment of my invention, it will be understood that minor changes in construction, combination, and arrangement of parts may be made without departing from the spirit and scope of the invention as claimed.

Having thus described my invention, what I claim is:—

15 A car having a first and a second inwardly swinging door, relatively narrow flange means on the exterior of the first door overlapping the exterior of the second door and being disengageable from the second door through limited inward swinging 20 movement of both doors, an exterior fastening means disposed longitudinally on the

second door to engage the car adjacent the top and the bottom of the doors to prevent movement of both doors relative to the car, said fastening means also being disposed 25 relatively close to the free edge of the second door to relieve said flange means of undue outward pressure, one of said doors having a plurality of independently operable sections, and each of the sections having an interiorly disposed flange depending therefrom and crossing its junction with and engaging the adjacent section to further relieve said first mentioned flanges of undue outward pressure.

30 In testimony whereof I affix my signature in presence of two witnesses.

GEORGE M. DE VILBISS.
